(57) **CLAIM**

The ornamental design for a handle for kitchen gadgets, as
shown and described.

DESCRIPTION

FIG. 1 is a perspective view of handle for kitchen gadgets
embodiment our design with dashed lines to illustrate environment;

FIG. 2 is another perspective view thereof;

FIG. 3 is a front elevational view thereof; the rear elevational
view being a mirror image thereof;

FIG. 4 is a top plan view thereof; the bottom plan view being
a mirror image thereof;

FIG. 5 is a right elevational view thereof; and,

FIG. 6 is a left elevational view thereof.

The dashed lines in FIG. 1 illustrate environment only and
form no new part of the claimed design.
